UNITED STATES PATENT OFFICE.

HENRY BRYCE, OF COHOES, NEW YORK.

WING-COLLAR.

1,152,483.

Specification of Letters Patent.

Patented Sept. 7, 1915.

Application filed October 23, 1912. Serial No. 727,336.

To all whom it may concern:

Be it known that I, HENRY BRYCE, a citizen of the United States, residing at Cohoes, county of Albany, and State of New York, have invented certain new and useful Improvements in Wing-Collars, of which the following is a specification.

The invention relates to such improvements and consists of the novel construction and combination of parts hereinafter described and subsequently claimed.

Reference may be had to the accompanying drawings, which form a part of this specification. Similar characters refer to similar parts in the several figures therein.

Figure 1 of the drawings is a plan view of the outer side of a collar embodying my invention, one end only of the collar being shown. Fig. 2 is a similar view of the inner side of the collar. Fig. 3 is a plan view of the inner side of the outer surface-ply with its edges inturned and the buttonhole-tab facing with inturned edges superimposed thereupon. Fig. 4 is a plan view of the inner side of the inner surface-ply with its edges inturned and the wing-facing with its edges inturned superimposed thereupon. Fig. 5 is a cross-section taken on the broken line 5—5 in Fig. 3. Fig. 6 is a cross-section taken on the broken line 6—6 in Fig. 4. Fig. 7 is a cross-section taken on the broken line 7—7 in Figs. 1 and 2. Fig. 8 is a cross-section taken on the broken line 8—8 in Figs. 1 and 2.

The invention relates to the style of standing collar which has at its ends buttonhole tabs, and wings adapted to be folded back upon the body of the collar.

The principal object of the invention is to make practicable the manufacture of such a collar by the use of folding or turning machines, and to provide the collar with a guide for the fold of the wing, while maintaining continuity of an inner surface-ply of the collar and the corresponding surface-ply of the wing.

Referring to the drawings wherein the invention is shown in preferred form, 1, represents the outer surface-ply, and, 2, the inner surface-ply of the collar. The outer surface-ply, 1, is formed with an integral buttonhole-tab end, 3, and terminates at, 4, at the fold line of the wing. The inner sur-

face-ply is formed with an integral wing-end, 5, and terminates short of the button-hole-tab end, 3, as shown in Fig. 2. The two surface-plies, 1 and 2, have their edges inturned on all sides as shown at 7.

In superimposing the surface-plies, 1 and 2, upon one another, the wing-portion, 5, of the inner surface-ply is left uncovered by the outer surface-ply, and the buttonhole-tab end portion, 3, of the outer surface-ply is left uncovered by the inner surface-ply.

To complete the wing and buttonhole-tab, I superimpose upon the wing-portion, 5, of the inner ply, a wing-facing, 8, having its edges inturned as shown at, 9, and I superimpose upon the tab end of the outer ply, a tab-facing, 10, having its edges inturned as shown at 11.

The wing-facing and the tab-facing, both extend in between the body-portions of the two surface-plies, 1 and 2.

With the respective plies and facings thus superimposed and arranged, the collar is stitched through and through along all the edges of its surface-plies, thus securing the surface-plies together and the tab and wing-facings to their respective surface-plies.

The inturned stitched edge, 4, of the outer ply forms a guide for folding over the wing.

The inner surface-ply, 2, and the corresponding surface-ply of the wing, 5, are continuous and integral so that at the fold line of the wing, there is exposed to the neck of the wearer only a rounded surface of a continuous piece of fabric.

A collar constructed in this manner has its respective surface-plies forming one side only of the angle, 12, between the wing and the buttonhole-tab, so that it is possible to machine-turn both the front and back blanks, however acute said angle may be.

For convenience of illustration, I have shown the body of the collar formed of two plies only, but it will be understood that any desired number of plies may be employed.

The stitching is shown at 13.

What I claim as new and desire to secure by Letters Patent is—

A standing collar having end buttonhole-tabs, and wings forming reentrant angles with said buttonhole-tabs, said collar comprising a plurality of plies and having one

of its surface plies wholly covering one side of the collar, except said wings, and its other surface ply wholly covering the other side of the collar, except said buttonhole-tabs and separate facings for the wing and tab.

In testimony whereof, I have hereunto set my hand this 19th day of October, 1912.

HENRY BRYCE.
